United States Patent Office

Des. 189,458
Patented Dec. 20, 1960

189,458

KITE

John W. Jordan, 608 E. Forrest, Victoria, Tex.

Filed Sept. 26, 1960, Ser. No. 62,255

Term of patent 14 years

(Cl. D34—15)

Figure 1 is a perspective view of a kite showing my new design; Figure 2 is a side elevational view; and Figure 3 is an end elevational view.

I claim:

The ornamental design for a kite, as shown.
